TOMATO PACKAGING CARTON OR SIMILAR ARTICLE

William B. Hirshon, Everett, Mass.

Application September 23, 1948, Serial No. 148,721

Term of patent 3½ years

(Cl. D80—5)

To all whom it may concern:

Be it known that I, William B. Hirshon, a citizen of the United States, residing at Everett, in the county of Middlesex and State of Massachusetts, have invented a new, original, and ornamental Design for Tomato Packaging Carton or Similar Article, of which the following is a specification, reference being had to the accompanying drawing, forming part thereof.

In the drawing:

Fig. 1 is a top plan view of a tomato packaging carton or similar article, showing my new design;

Fig. 2 is a view in elevation of one side thereof, the other side having the same appearance;

Fig. 3 is an end view thereof; and

Fig. 4 is a sectional view on the line 4—4 of Fig. 1.

I claim:

The ornamental design for a tomato packaging carton or similar article, substantially as shown.

WILLIAM B. HIRSHON.
